COMBINED FLOOD AND SEARCH LIGHT OR SIMILAR ARTICLE

Jeremiah D. Kennelly and Harry E. Williams, Oak Park,
Ill., assignors to Mars Signal-Light Company, Chicago,
Ill., a corporation of Illinois

Filed Feb. 13, 1959, Ser. No. 54,604

Term of patent 14 years

(Cl. D48—20)

Figure 1 is a top plan view of a combined flood and search light showing our new design;

Figure 2 is a front elevational view thereof;

Figure 3 is an elevational view thereof as seen from the left of Fig. 2;

Figure 4 is an elevational view thereof as seen from the right of Fig. 2 with a portion omitted for convenience of illustration;

Figure 5 is a rear elevational view thereof; and

Figure 6 is a sectional plan view of a portion thereof, the section being taken on line 6—6 of Fig. 2.

We claim:

The ornamental design for a combined flood and search light or similar article, as shown.
